UNITED STATES PATENT OFFICE.

CHARLES SPAULDING, OF MALDEN, MASSACHUSETTS.

DIVIDING MECHANISM FOR GEAR-CUTTING MACHINES.

SPECIFICATION forming part of Letters Patent No. 376,833, dated January 24, 1888.

Application filed May 2, 1887. Serial No. 236,874. (No model.)

To all whom it may concern:

Be it known that I, CHARLES SPAULDING, a citizen of the United States, residing at Malden, in the county of Middlesex and State of Massachusetts, have invented new and useful Improvements in Dividing Mechanisms for Gear-Cutting Machines, of which the following is a specification.

My invention relates to that class of dividing-machines which are used in connection with machines for cutting gears for the purpose of dividing up the blanks into the several divisions required for the various numbers of teeth; and the objects of my invention are, first, to produce any desired division on the periphery of the blank with exactly the same movement of hand or power, which not only simplifies the working of the machine, but also prevents the liabilities of mistakes from placing the pin in the wrong hole on the index-plate each time the blank is moved, and, second, in automatic gear-cutting machines to save the cost of the large number of change-gears required and used for dividing the blanks and the time required for removing the said change-gears and replacing them by others each time a gear-blank requiring a different number of teeth is placed upon a machine. I attain these objects by the mechanism illustrated in the accompanying drawings, in which—

Figure 1 is a side view of my invention adapted to an ordinary gear-cutting machine. Fig. 2 is a front view of same. Fig. 3 is a section on line *xx* of Fig. 2. Figs. 4 and 5 are diagrams illustrating the theory of my invention. Fig. 6 is a detail drawn in perspective, showing automatic way of moving index-plate.

A, Figs. 1 and 3, is a standard for supporting shaft or spindle B, upon which the blank C is placed.

D represents the position of the cutter (in dotted lines) with reference to the blank C. Upon the other end of the spindle B is placed the index-plate E, the said plate being fastened by the set-screw *b'* to the spindle B. It is obvious that by turning the index-plate E the blank C will be also turned an equal angle.

F, Figs. 1 and 2, is a sliding plate supported and guided by the uprights G G'. This sliding plate has a slot, *f*, extending vertically

from near the center of the index-plate to the periphery thereof. The movement of the sliding plate is accomplished by moving the handle H, and said movement may be accurately adjusted and limited by the screws *f' f''*, supported by lugs on said plate.

Projecting from the center of the index-plate is the spindle *b*, Fig. 3, which is used for guiding the movement of the slotted arm J. This arm J is slotted to allow the pin K to be placed at any distance required from the center of the index-plate. The pin K, being provided at one end with the thumb-nut *k*, can be clamped firmly to the arm J, so that any movement given to the pin K will be given also to the arm J, which may or may not be provided with a scale marked thereon for the purpose of setting the pin K at any required distance from the center. The opposite end of the pin K is turned down to a smaller diameter to fit holes *m m* of the index-plate. The largest part of this pin K accurately fits the slot *f*. Now if the sliding plate F is moved a certain distance each time a groove is to be cut in the blank, the same movement will be communicated to the index-plate by the pin K, and also to the slotted arm J. The pin K, being fastened to the slotted arm J, will be moved in the arc of a circle by the rectilinear movement of the sliding plate F. The pin K is moved into and out of the holes in the index-plate by moving the arm J laterally by means of the rock-shaft I'', lever I, and handle I', Figs. 1 and 2. The distance between successive holes in the index-plate corresponds exactly with the distance which the sliding plate F moves. The larger the diameter of the circle in which these holes are made the greater number of holes there will be in the circumference. The method of finding the exact diameter of the various circles containing the required number of holes with a given distance between them will be shown presently.

The operation of this machine is as follows: The workman clasps the two handles H I', moving the latter so as to disengage the pin K from the index-plate. When this is done, the thumb-nut *k* is loosened, and the pin K is free to be slipped along the slot to the required circle of holes, when it is tightened and allowed to snap back into the hole in the index-plate by the

tension of the spring j between the arm J and the nut l . When the pin is in the right circle of holes, the handles are again clasped, moving out the pin, as before, so as not to disturb the index-plate, which is held by the friction of its spindle B in the bearing A . The sliding arm F is then moved in the direction indicated by the arrow against the tension of the spring n , Fig. 2, until prevented from further movement by the screw f' . The handle I' is then released, allowing the pin K to snap into the next hole of the index-plate. The sliding plate F is then moved back into its original position by hand or by the heavy spring n , which presses against the pin n' . This moves the pin K the same distance, and consequently the index-plate E the required distance. The blank is then cut, and when ready to be turned to the position required for the next groove the operation of moving the index is gone through with as before, and is continued until the index has made one revolution, when the teeth on the gear will be entirely formed. In automatic machines the moving out of the pin K and the sliding of the plate F could be done automatically by cams, as shown in Fig. 6, when the shaft O would be given one complete revolution each time the dial-plate was to be moved. Any well-known device operated either from a separate belt or from any moving part of the machine can be used. This device would entirely dispense with the change-gears commonly used on automatic machines for dividing up the blank into the various numbers of equal divisions for cutting gears containing different numbers of teeth. The only operation required would be, after the blank has been put in position to be cut, to loosen the thumb-nut and slide the pin K along the slot until it entered the circle of holes corresponding with the number of teeth to be cut in the gear. The machine then would be started, and after each groove was cut the index-plate would be moved automatically one division at a time until a complete revolution had been made, when, as in ordinary machines, after the gear has been cut, the entire mechanism would stop.

Referring now to the diagram, Fig. 4, let a represent the center of the index-plate, and let b be the hole in which the pin K is placed. Now move the index-plate by the pin K till it reaches the point c , and draw radial lines from a through b and c . This will show the angle through which the index-plate, and consequently the gear-blank, moves when the pin K is placed at a distance, $a b$, from the center of index-plate. Now slide the pin along the slot until it enters the hole d and move index-plate, as before, the same distance, $d e$, equal to $b c$. Drawing radial lines, as before, through d and e from a shows also the angle through which the index moves when placed at distance $a d$ from the center, and the same through $f g$. Now in laying off the circles of holes on the index-plate the following is the method of

finding the radius of a circle containing the required number of holes: In Fig. 5, $h = \frac{i}{\sin O}$. Let the movement of sliding plate F equal one-fourth inch and the number of teeth to be cut sixty; the angle between each tooth is $\frac{360}{60} = 6^\circ$, one-half of which is three degrees, and one-half the movement is one-eighth inch, or $.125$. Then $h = \frac{.125}{\sin 3^\circ} = \frac{.125}{.05234} = 2.3882''$ = the radius of the circle having sixty holes with a distance of one-quarter inch between each.

As the difference between the concentric circles on the dial-plate on which the holes are laid out for successive numbers of teeth measures only about .04 inch, with this movement ($\frac{1}{4}$) it is necessary to have several index-plates, taking, say, every fourth number, as 20, 24, 28, 32, and so on, allowing more distance between the series of holes, and thus providing space for a larger pin which moves the index-plate.

It will be seen that the slide F and pin K are capable of conjoint action in rotating the index-wheel step by step; hence I do not limit myself to the use of the particular devices herein described for moving the pin K toward and from the index-wheel to engage it with and disengage it from said wheel, nor to any devices for this purpose, as said movements may be effected by hand. It is quite obvious, however, that it is desirable to provide some reliable means for effecting the described movements of the pin, and the devices herein described are as convenient and suitable as any of which I am at present aware.

I claim—

1. The combination of a rotary shaft adapted to hold a blank, an index-wheel attached to said shaft and having concentric rows of holes, each row having a different number of holes from the others, while the holes in all the rows are at uniform distances apart, an operating-slide which is adapted to be reciprocated across the face of the index-wheel a distance equal to the distance from hole to hole in any row of holes in the index-wheel, and provided with a slot extending radially of the index-wheel, across all the rows of holes therein, and a latch or pin passing through said slot and adapted to be engaged with any hole in the index-wheel coincident with the slot, said slide and pin operating conjointly to give the index-wheel and the blank-holding shaft step-by-step rotations, the extent of which is governed by the distance of the pin or latch from the axis of the index-wheel, as set forth.

2. The combination of a rotary blank-holding shaft, an index-wheel attached thereto and having concentric rows of holes, all the holes being spaced alike, while each row has a different number of holes, an operating-slide adapted to have a reciprocating motion, which is limited, as described, across the face of the

index-wheel and provided with a slot extending across all the rows of holes in the index-wheel, a latch or pin passing through said slot and adapted to be moved therein from one row of holes in the index-wheel to another, and devices whereby said pin may be alternately moved from and toward the index-wheel to disengage it from and engage it with holes in said wheel, as set forth.

10 3. The combination of the blank-holding shaft, the index-wheel thereon having the concentric rows of holes, the operating-slide F, having a slot, f, and provided with devices to limit its reciprocating movements, the latch 15 or pin K, adapted to slide in said slot toward and from the index-wheel and from row to row of holes therein, the slotted arm J, adapted both to oscillate and slide on a stud in line with the axial center of the index-wheel, and 20 engaged, as described, with the latch or pin K, and the rock-shaft I", having the arm I engaged with said arm J, whereby said arm and the latch or pin may be moved toward and from the index-wheel, as set forth.

25 4. The combination of the blank-holding shaft, the index-wheel thereon having the concentric rows of holes, the operating-slide F, having the slot f and provided with devices to limit its reciprocating movements, the latch 30 or pin K, adapted to move, as described, in said slot, the slotted arm J, adapted both to oscillate and slide on a stud in line with the axial center of the index-wheel, the spring j, whereby the arm J is normally pressed toward 35 the index-wheel to engage the pin K with a hole therein, and the rock-shaft I", having the arm I engaged, as described, with the arm J,

whereby the latter may be moved against the pressure of the spring j to remove the pin K from the index-wheel, as set forth.

5. The combination of the blank-holding shaft, the index-wheel having holes arranged as described, the latch or pin K, the operating-slide F, having the slot f, receiving said pin, the stops f' f" on said slide, and a fixed stop, 45 as G', co-operating with said stops f' f", as set forth.

6. The combination of the blank-holding shaft, the index-wheel having holes, arranged as described, the latch or pin K, the operating-slide F, having the slot f, receiving said pin, the adjustable stops f' f" on said slide, the spring n, arranged to move said slide in one direction, and a handle, H, whereby the slide may be moved in the opposite direction, 55 as set forth.

7. The combination of the blank-holding shaft, the index-wheel having holes, arranged as described, the latch or pin K, the operating-slide F, having the slot f, receiving said pin and the handle H, the stops f' f" on said slide, the fixed stop G', the slotted arm J, adapted both to oscillate and slide, the spring j, arranged to hold the arm J in its normal position, and the rock-shaft I", having the arm I engaged with the arm J, and the handle I', arranged in close proximity to the handle H, whereby both handles may be grasped simultaneously, as set forth.

CHARLES SPAULDING.
